UNITED STATES PATENT OFFICE.

LOUIS V. ARONSON, OF NEWARK, NEW JERSEY.

DESIGN FOR A RADIATOR-EMBLEM.

48,165.

Specification for Design.

Patented Nov. 23, 1915.

Application filed July 12, 1915. Serial No. 39,495. Term of patent 7 years.

To all whom it may concern:

Be it known that I, LOUIS V. ARONSON, a citizen of the United States, residing in the city of Newark, in the county of Essex and State of New Jersey, have invented a new, original, and ornamental Design for Radiator-Emblems; and I do hereby declare the following to be a full, clear, and exact description of the invention, reference being had to the accompanying drawings, which form a part of this specification.

Figure 1 represents a front elevation of my improved design; and Fig. 2 represents a plan view of the same.

As shown in the drawings, my design consists of a base, having cast integrally there-

with two flagstaffs, at an angle to each other. Mounted on each flagstaff, in an extended position, is an American flag. Interposed between the flagstaffs and integrally cast therewith, are two metal bands or strips, the upper curved and the lower straight, on which are mounted the words "America first."

I claim:

The ornamental design for a radiator emblem, as shown and described.

LOUIS V. ARONSON.

Witnesses:

ALEXANDER HARRIS,
FREDK. C. FISCHER.
